Primary Examiner — Jennifer L Rempfer*Assistant Examiner* — Olivia H Aldin(74) *Attorney, Agent, or Firm* — Browdy and Neimark, PLLC(57) **CLAIM**

The ornamental design for a Venetian blind slat clip, as shown and described.

DESCRIPTION

FIG. 1 is a perspective view of a Venetian blind slat clip showing the claimed design;

FIG. 2 is a front view thereof;

FIG. 3 is a rear view thereof;

FIG. 4 is a left side view thereof;

FIG. 5 is a right side view thereof;

FIG. 6 is a top view thereof;

FIG. 7 is a bottom view thereof; and,

FIG. 8 is a perspective view showing that the Venetian blind slat clip is coupled with a Venetian blind slat.

The broken lines in FIG. 8 show a Venetian blind slat and form no part of the claimed design.

1 Claim, 7 Drawing Sheets(56)
